United States Patent

Des. 240,948
Patented Aug. 10, 1976

240,948

GOLF CLUB HEAD

Joseph F. Redoutey, 4305 Quando Lane,
Orlando, Fla. 32809

Filed Feb. 14, 1975, Ser. No. 549,987

Term of patent 14 years

Int. Cl. D21—02

U.S. Cl. D34—5 GH

Fig. 2.

Fig. 1.

Fig. 3.

Fig. 4.

Fig. 5.

FIG. 1 is a top plan view of a golf club head showing my new design;

FIG. 2 is an end elevational view taken from the left of FIG. 1;

FIG. 3 is an end elevational view taken from the right of FIG. 1;

FIG. 4 is a rear elevational view; and

FIG. 5 is a front perspective thereof.

I claim:

The ornamental design for a golf club head, as shown and described.
